AIR CIRCULATING FAN

John H. Beckert, Los Angeles, Calif.

Application September 30, 1946, Serial No. 700,306

7 Claims. (Cl. 230—259)

1

This invention relates to air circulating fan and has its general object to provide a fan that is adapted to circulate air in all directions.

A specific object of the invention is to provide a fan adapted to deliver air from both the peripheral and the side areas thereof including the central or axial regions.

A further object of the invention is to provide a fan having a double impeller adapted to deliver air in substantially all directions to produce a movement of air generally similar to an expanding globe.

Another object of the invention is to provide a fan including an impeller and driving means therefor supported upon a base that lies beneath the impeller, which fan is adapted to deliver air in all directions except directly downwardly (the downward direction of delivery being obstructed by the base).

A particular object of the present invention is to provide an air circulating fan of the type specified above in which a power unit that drives the impeller is disposed within the confines of the impeller.

Another object of the invention is to provide an air circulating fan embodying a motor and an impeller encompassing the motor and including novel and improved means for circulating a portion of the air that is delivered by the impeller, axially through the motor so as to cool the same.

Other objects will become apparent in the ensuing specification and appended drawings, in which:

Fig. 1 is a side view of an air circulating fan embodying my invention;

Fig. 2 is a front elevation of the impeller;

Fig. 3 is a sectional view taken on the line 3—3 of Fig. 2;

Fig. 4 is a sectional view taken on the line 4—4 of Fig. 1;

Fig. 5 is a detailed sectional view taken on the line 5—5 of Fig. 4;

Fig. 6 is an axial sectional view of the hub portion of the impeller and the driving mechanism, taken on the line 6—6 of Fig. 2; and,

Fig. 7 is a front elevation of an impeller embodying a modified form of the invention.

As an example of one form in which my invention may be embodied, I have shown in the drawings an air circulating fan adapted to be employed for producing a gentle movement, in all directions, of air in a room or other confined air space. The fan has a pedestal including an upright 4 and a base 5 that is adapted to rest upon a table or other supporting surface.

2

At its upper end, the upright 4 is formed with a head 6 that has a rear surface 7 and a forward surface 8 each of which is concave and defined as a surface of revolution of a curved line. For example, the surfaces 7 and 8 may be paraboloid. Where the surfaces 7 and 8 meet, they define a sharp edge 9.

Supported upon the forward end of the head 6 is an electric motor which is indicated generally at 10. The motor 10 is received within the hub sleeve 13 of an impeller 14. The motor 10 includes a case 11 that is mounted upon a collar 12 on the head 6, and is separated from the sleeve 13 by an annular space 15 that provides for circulation of air axially therethrough, around the motor, for cooling the same. Mounted within the collar 12 is a bearing 21 in the inner race of which is secured the motor shaft 22.

The sleeve 13 is mounted upon the shaft 22 through the medium of a clutch member 23 comprising an integral collar on the shaft 22 and a pair of pins 24 projecting from the collar, a hub member 25 joined to the sleeve 13 by blades 26, and a nut 27 that is threaded at 28 onto the end of the shaft 22. The hub member 25 has recesses in which the pins 24 are clutched, and the nut 27 secures the parts in assembly. By removing the nut 27, the hub 25 may be slipped off the shaft 22. As shown, the hub 25, blades 26 and sleeve 13 are formed integrally, although it will be understood that they may be constructed separately and suitably secured together. The nut 27, hub 25 and collar 23 form a faired core device which cooperates with the sleeve 13 to define the annular air flow passage 15 which converges at its forward end, as at 29, the forward end of the sleeve 13 being curved inwardly as at 30.

The blades 26 constitute a ventilating fan in the passage 15. Referring now to Fig. 5, the leading edges 31 of the blades 26 are bluntly curved, while the trailing edges 32 are feathered out, the blades thus being of air foil cross section. The direction of rotation of the impeller and ventilating fan is indicated by the arrows 33 in Figs. 2 and 5, and the direction of air flow through the duct 29 is indicated by the arrows 34 in Figs. 5 and 6, respectively.

The impeller 14 includes a plurality of double blades which are shaped so as to deliver air peripherally and axially in both directions. Each of these blades includes a pair of air ducts 35, each of which is shaped generally similar to a cornucopia and has an inlet 36 and an outlet 37. The inlets 36 of one pair of ducts are located in

the forward face of a respective blade, whereas the outlets 37 of these same ducts are located ahead of the forward face of a succeeding blade. At its inlet end, each duct 35 is flared outwardly to a maximum cross sectional area, and it gradually decreases in cross section area from the inlet 36 to the outlet 37. The axis of each duct 35 is spiral shaped, in a plane normal to the axis of the shaft 22, and gradually approaches the shaft 22 from the inlet 36 to the outlet 37. The spiral axes of the ducts of one blade lie in a common plane with the spiral axes of the ducts of the other blade. The inner end of each duct is extended into a space defined between the sleeve 13 and the outer, or inlet end, of an opposed duct.

Radiating in an arc of somewhat more than 180 degrees from each pair of duct inlets 36 is a fan blade including a pair of axially extending portions 38, a radially extending peripheral portion 39, and curved intermediate portions 40 joining the peripheral portion 39 and the axially extending portions 38. These several blade portions are swept rearwardly with reference to the direction of blade movement and collectively present a composite forward surface that is concave but generally frustoconical. This is, from a mouth 36, the blade portions 38 are inclined rearwardly and axially, the blade portion 39 is inclined rearwardly and radially outwardly, and the blade portions 40 are inclined rearwardly and in directions intermediate the axial and radial. Consequently the air encountered by the inclined surfaces will be thrown off the blades in all directions throughout a substantially peripheral surface of revolution of the fan impeller, axially toward the head 6 as indicated by the arrows 41, radially outwardly as indicated by the arrows 42 and axially away from the head 6 as indicated by the arrows 43.

The air, moving in the direction 41 past the sharp edge 9 of the head 6, creates a turbulence that is indicated by the arrow 44. This turbulence resists the air movement past the edge 9, tending to seal the exit in the direction 44 in the inner region of the impeller. Consequently, the air thrown axially from the innermost portions of the blade members 38 will be deflected inwardly into the sleeve 13 as indicated by the arrows 45. The inclined surface 8 of the head 6 directs the air currents 45 into the sleeve 13. The ventilating fan blades 26 at the other end of the sleeve 13 cooperate with the pressure head thus set up by the air currents 45, to create the circulation 34 through the sleeve 13 and through the motor 15.

The slope of the lateral portions 38 of the fan blades varies from the inner to the outer extremities of these lateral portions. At the outer extremities, there is a gradual slope from the mouth 36 of the duct 35 to the lateral edges of the blade portions 38, as indicated at 46 in Fig. 3. The inner extremities of the blade portions 38, lying between the mouth portions 36 of the ducts 35 and the sleeve 13, extend axially as indicated at 47, in Fig. 3, to points beneath the lateral walls of the discharge end 37 of the other duct, and then are sloped as at 48 to the web wall 49, so as to provide space for the discharge of air from the discharge ends 37 of the ducts.

In the operation of my improved air circulating fan, there will be an induction or inward movement of air into the center of the region swept by the impeller 14, along the periphery of the sleeve 13. A portion of the air thus brought to the center of the impeller will be scooped up by the inlets 36 and forced through the ducts 35 to the outlets

37 thereof, from which the air will be discharged circumferentially against the sloping surfaces 48 and thereby deflected axially outwardly as indicated by the arrows 50 in Fig. 3. The remainder 5 of the air inducted to the center of the impeller will be engaged by the inclined blade portions 38, 39 and 40 and will thereby be thrown outwardly in all directions as indicated by the arrows 41, 42 and 43. Due to the reduction in cross sectional area of ducts 35 from the inlets to the outlets thereof, the air passing through these ducts will have its velocity accelerated. This tends to speed up the movement of air discharged from the central region of the fan and provides for substantially as much movement of air in the axial regions encompassed within the extended periphery of the sleeve 13, as in the outer regions of air discharged from the impeller. Thus the invention provides for a substantially uniform flow of air from the fan in all directions. This flow is comparatively gentle, since the fan is not designed for the projection of a high velocity concentrated air stream, but rather for a low velocity, defused air movement in all directions. This is a desirable characteristic in an air circulating fan for ventilating purposes.

The only direction in which the fan does not deliver air, is the downward direction, in which the air currents delivered from the fan are blocked 30 and deflected outwardly by the base 5. This is an advantageous feature, since downward delivery of air from the fan is not desired.

In the modified form of the invention shown in Fig. 7, the impeller has three instead of two blades, 35 and the ducts 35^a are somewhat shorter. The three bladed impeller will deliver approximately 50% more air to the sleeve 13 and will circulate approximately 50% more air than the two bladed impeller.

I claim as my invention:

1. In an air circulating fan, a motor through which air may be circulated in an axial direction; an impeller having a hub sleeve open at one end and surrounding said motor and having a plurality 45 of fan blades thereon shaped to deliver air both radially and axially; and a support for said motor and impeller including a head portion providing an annular barrier disposed adjacent the open end of said sleeve and extending radially beyond 50 the open end of said sleeve and in the path of air currents discharged axially from said impeller adapted to deflect some of said air currents inwardly into said hub sleeve.

2. In an air circulating fan, a motor through 55 which air may be circulated in an axial direction; an impeller having a hub sleeve open at one end and surrounding said motor and having a plurality of fan blades thereon shaped to deliver air both radially and axially; a support for said motor and impeller including a head portion providing an annular barrier disposed adjacent the open end of said sleeve and extending radially beyond the open end of said sleeve and in the path of air currents discharged axially from said impeller, adapted to 60 deflect some of said air currents inwardly into said hub sleeve; and a ventilating fan within said hub sleeve at the opposite end of said motor from said head.

3. In a ventilating fan, an impeller including 70 a hollow hub sleeve open at one end and having blades thereon adapted to discharge air axially and radially, an electric motor within said hub sleeve, through which a ventilating current of air may pass axially, and a support having a head on which said motor is mounted, said head

including an annular barrier that is disposed adjacent the open end of said sleeve and cooperating with the surface of revolution of the inner end extremities of the impeller blades to define an annular air passage extending inwardly and toward said motor and increasing in width toward its inner extremity, said annular barrier extending radially beyond said sleeve in order to deflect into said hub sleeve, currents of air delivered axially from said impeller blade.

4. In a ventilating fan, an impeller including a hollow hub sleeve open at one end and having blades thereon adapted to discharge air axially and radially, an electric motor within said hub sleeve through which a ventilating current of air may pass axially, a support having a head on which said motor is mounted, said head including an annular barrier that is disposed adjacent the open end of said sleeve and cooperating with the surface of revolution of the inner end extremities of the impeller blades to define an annular air passage extending inwardly and toward said motor and increasing in width toward its inner extremity, said annular barrier extending radially beyond said sleeve in order to deflect into said hub sleeve currents of air delivered axially from said impeller blade, and a ventilating fan in said hub sleeve on the opposite side of said motor from said barrier.

5. In an air circulating fan, an impeller having a hub sleeve open at one end, and blades adapted to discharge air axially and radially, an electric motor within said hub sleeve, connected to said impeller for driving the same, and a support having a head on which said motor is mounted, said head including an annular barrier having a sharp edged periphery disposed adjacent the open end of said sleeve and extending radially beyond the sleeve and in the path of some of the air currents delivered axially from said blades, said barrier deflecting some of said air currents inwardly into said hollow hub sleeve.

6. In an air circulating fan, an impeller having a plurality of blades shaped to deliver air in all directions from the center thereof and having corresponding air ducts, each having an inlet in the forward face of one blade and an

outlet discharging ahead of and toward the forward face of a succeeding blade, the blades having inclined portions adapted to deflect in an axial direction the discharge from said outlets, 5 said impeller having a hub sleeve open at one end, an electric motor within said hub sleeve; and a support for said motor and impeller including a head portion providing an annular barrier disposed adjacent the open end of said sleeve and 10 extending radially beyond said sleeve and into the path of air currents discharged axially from said impeller to deflect some of said air currents inwardly into said hub sleeve.

7. In an air circulating fan, an impeller having a plurality of blades shaped to deliver air in 15 all directions from the center thereof and having corresponding air ducts, each having an inlet in the forward face of one blade and an outlet discharging ahead of and toward the forward face 20 of a succeeding blade, the blades having inclined portions adapted to deflect in an axial direction the discharge from said outlets, said impeller having a hub sleeve open at one end, an electric motor within said hub sleeve, through which a ventilating current of air may pass axially, and a support having a head on which said motor is mounted, said head including an annular barrier disposed adjacent the open end of said sleeve and 25 extending radially beyond said sleeve and cooperating with the surface of revolution of the inner end extremities of the impeller blades to define an annular air passage extending inwardly and toward said motor and increasing in width toward its inner extremity, said annular barrier deflecting into said hub sleeve, currents of air delivered axially from said impeller blade.
